UNITED STATES PATENT OFFICE.

CHARLES HENRY SPENCE, OF ST. PAUL, MINNESOTA.

GRAVITY-CONVEYER.

No. 872,856.

Specification of Letters Patent.

Patented Dec. 3, 1907.

Application filed July 31, 1907. Serial No. 386,392.

To all whom it may concern:

Be it known that I, CHARLES H. SPENCE, a citizen of the United States, residing at St. Paul, in the county of Ramsey and State of Minnesota, have invented a new and useful Gravity-Conveyer, of which the following is a specification.

This invention relates to gravity conveyers and has for its principal object to provide a conveyer section to be used where the articles being delivered are to be conveyed around a curve.

A further object of the invention is to provide a curved conveyer section which may be conveniently placed between two straight conveyers where the articles must travel in an indirect path to a point of delivery.

A still further object of the invention is to provide a curved conveyer section having frusto-conical rollers which are arranged in staggered order and held out of contact with each other in order to permit independent revoluble movement and in which the diameter of the rollers gradually increases from the side of small radius to the side of larger radius.

A still further object of the invention is to provide a structure in which a series of spaced shafts radiating from a common center are each provided with spaced rollers all of frusto-conical form, the diameters of the rollers gradually increasing on radial lines from the common center, while the upper surfaces of all of the rolls of each shaft are disposed in a common horizontal plane, so that the surface speed will be greatest at the outer side of the conveyer.

A still further object of the invention is to provide a construction of conveyer in which the shafts are mounted in suitable ball bearings, so that they may freely turn with the rollers or independent of the rollers in order not to interfere with free movement in case one of the rollers should tend to bind on the shaft.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the

structure may be made without departing from the spirit or sacrificing any of the advantages of the invention.

In the accompanying drawings:—Figure 1 is a plan view of a curved conveyer constructed in accordance with the invention. Fig. 2 is a transverse sectional view of the same drawn to an enlarged scale. Fig. 3 is a detail sectional view on the line 3—3 of Fig. 2. Fig. 4 is a side elevation of a portion of the conveyer showing more particularly the detaching means for connection to an adjacent conveyer section. Fig. 5 is a plan view showing the application of the invention to a straight conveyer section. Fig. 6 is a transverse sectional view of the same on the line 6—6 of Fig. 5.

Similar numerals of reference are employed to indicate corresponding parts throughout the several figures of the drawings.

The conveyer forming the subject of the present invention is designed principally for use as a detachable section to be placed between two straight conveyers where articles are to be delivered in other than a straight line, and provision is made for readily connecting and disconnecting, as required.

The main frame comprises two side bars 10 and 11 preferably formed of, or including upper and lower channel bars, the side bars 85 being both struck from the same center, and the inner bar 10 being of less radius than the outer bar. These bars are provided at intervals with plates or blocks 15 which carry ball races 16 and between the bars extend 90 shafts 17, the axes of which are arranged on lines struck from the center from which the curves of the side bars are struck, and all of those shafts are disposed at a slight angle to the horizontal, their outer ends being 95 lowermost. Each shaft carries a ball race 18 between which and the ball race 16 are arranged anti-friction balls in order to permit free turning of the shafts, and these ball races are protected by suitable caps 19 100 which may be removed when necessary. Mounted on the shafts are rollers 20, all of the rollers being preferably formed of hard wood, boiled in tallow, and a number of such rollers being placed on each shaft. In the 105 present instance, each alternate shaft carries three rollers, and each intermediate shaft two rollers. The rollers are spaced

from each other by sleeves 22, so that the rollers on one shaft are held from contact with those of adjacent shafts.

- All of the rollers are frusto-conical in form, their tapering peripheral lines being struck from a common center before mentioned, and the roller at the inner end of the shaft being much smaller than the roller at the outer end, so that the surface speed of the conveyer gradually increases toward the outer or larger end. The upper surfaces of the rolls of each shaft are arranged in a common horizontal plane, so that the articles being unloaded will not be tipped sideways as they travel over the rollers, this being of importance from the fact that the conveyer may thus be more readily connected to and more effectually operated in connection with ordinary straight conveyers or chutes.

In order to prevent accidental dislodgment of articles when they strike the curved portion of the conveyer, the side rail or bar 11 is provided with vertical posts 25 which carry a curved strip 26 having openings through which project rollers 28, the axes of which are at a right angle to the general plane of the conveyer. These rollers are mounted in suitable bearings 27 and are so disposed that they may be engaged by articles that are carried on to the curved portion of the conveyer at abnormal speed.

At the opposite ends of the conveyer are locking bolts 30 which may be connected to pins 31 on the straight conveyer sections x.

The invention may, also, be applied to straight conveyer sections, as shown for instance in Figs. 5 and 6. In this case the rollers 20' are preferably cylindrical in form, but the rollers of each of the shafts 17' are held in spaced relation by sleeves 22'. The ends of the shafts are mounted in ball bearings in the side bars, while both sides of the conveyer are provided with the guarding and deflecting rollers 28 previously described.

I claim:—

1. In a curved gravity conveyer, a plurality of radially arranged shafts, a plurality of frusto-conical rollers arranged on each shaft, and spacing means on the shafts for

holding each roller from contact with the others.

2. In a curved gravity conveyer, a plurality of radially arranged shafts, a plurality of frusto conical rollers arranged on each shaft, spacing means on the shafts for holding each roller from contact with the others, the rollers of each shaft intersecting those of adjacent shafts.

3. In a curved gravity conveyer, a series of radially disposed shafts, a set of frusto conical rollers arranged on each shaft, spacing means on the shafts for holding each roller from contact with the others, and the rollers of each shaft intersecting the rollers of adjacent shafts.

4. In curved gravity conveyers, a plurality of radially disposed shafts, a set of frusto-conical rollers arranged on each shaft, spacing sleeves surrounding the shafts at points between the rollers, and means for supporting said shafts.

5. In curved gravity conveyers, a plurality of radially arranged shafts, frusto-conical rollers mounted on the shafts, the upper or load carrying surfaces of all of the rollers of each shaft being disposed in a common horizontal plane.

6. In curved gravity conveyers, a series of radially disposed shafts, frusto-conical rollers mounted on the shafts and having their upper surfaces in a common horizontal plane, and spacing means between said rollers.

7. In a curved gravity conveyer, a pair of side bars, ball bearings supported thereby, radial shafts in said ball bearings, frusto-conical rollers arranged on the shafts, spaced posts extending upward from the outer side bar, a curved strip carried by said posts, and a series of rollers supported by the strip and having portions of their peripheries extending through openings in said strip.

In testimony that I claim the foregoing as my own, I have hereto affixed my signature in the presence of two witnesses.

CHARLES HENRY SPENCE.
